UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 23, 1924. Serial No. 694,605.

My invention relates to railway traffic controlling apparatus, and particularly to apparatus of the type wherein governing apparatus located on a car or train is controlled by train governing currents supplied to the trackway.

I will describe certain forms of apparatus embodying my invention, and will then point out the novel features thereof in 10 claims.

In the accompanying drawings, Fig. 1 is a diagrammatic view showing one form of apparatus embodying my invention. Fig. 2 is a view showing in detail a translating 15 and rectifying apparatus represented by the rectangles D in Fig. 1, and also embodying my invention. Fig. 3 is a view showing a modification of a portion of the apparatus shown in Fig. 2 and likewise embodying my 20 invention.

Similar reference characters refer to similar parts in each of the views.

Referring first to Fig. 1, the reference characters 1 and 2 designate the track rails 25 of a railway along which traffic normally moves in the direction indicated by the arrow. These rails are divided by insulated joints 3 into a plurality of sections, of which only two sections, A—B and B—C, are 30 shown in the drawing.

Each section is provided with a motor generator designated by the reference character E, with an exponent corresponding to the location. Each of these motor generators 35 comprises a motor M driving two generators G⁵ and G⁶. The motor M receives current from the secondary 7 of a transformer designated by the reference character T, with an exponent corresponding to 40 the location, and the primary 45 of each transformer T is constantly supplied with alternating current from a generator G, through a transmission line 44.

The frequencies of the currents supplied 45 by transformer secondary 7 and generators G⁵ and G⁶, which I will term "train governing currents", are different, and may be of any desired values. As an example, the frequency of the current supplied by secondary 50 7 may be 60 cycles per second, the frequency of the current supplied by generator G⁶ may be 150 cycles per second, and the frequency of the current supplied by

generator G⁵ may be 250 cycles per second, but I do not wish to be limited to currents 55 of these or any other specific frequencies. For convenience I will hereinafter refer to these currents as frequencies 7, 6 and 5 respectively.

Each track section is provided with a 60 track relay designated by the reference character Q with an exponent corresponding to the location, which relay in the form here shown comprises two windings 46 and 47. The winding 46 is connected across the 65 track rails adjacent the entrance end of the section, and the winding 47 is supplied with alternating current from the secondary 12 of the adjacent transformer T. It follows that each relay Q is responsive to current 70 in the track rails of the frequency supplied by transformer secondary 7, but not to current in the track rails of the frequencies supplied by generators G⁵ and G⁶, and it also follows that each track relay is responsive to reversals of the relative polarity of 75 the current in the track rails from secondary 7.

The supply of train governing current to the rails of each section is controlled 80 by contacts on the track relay Q for the section next in advance. Referring specifically to section B—C, when track relay Q^c is de-energized current from secondary 7 of transformer T^c is supplied to the track 85 rails at the exit end of the section by contacts 8 and 8^a and the current in the rails due to this source has one relative polarity. When relay Q^c is energized in either direction current from secondary 7 of transformer T^c continues to be supplied to the 90 rails at the exit end of section B—C by contacts 8 and 8^a, but this current is now of the opposite relative polarity.

When relay Q^c is de-energized, current is 95 not supplied to section B—C from generator G⁵, because track relay contacts 9 and 9^a are open. When relay Q^c is energized in either direction, however, contacts 9 and 9^a are closed, so that current from generator 100 G⁵ is then supplied to the track rails at the exit end of section B—C and the relative polarity of this current is the same regardless of the direction in which relay Q^c is energized.

When relay Q^c is de-energized, so that

its back contacts 10 and 10^a are closed, current from generator G^e is supplied to the rails at an intermediate point X in section B—C, but when relay Q^c is energized 5 in either direction its contacts 10 and 10^a are open, so that the supply of current from generator G^e is discontinued. Point X is located at least at maximum braking distance in the rear of point C for trains moving 10 at an intermediate speed.

The supply of train governing currents to the rails of section A—B is controlled by track relay Q^b in the same manner as the supply of train governing currents to 15 the rails of section B—C is controlled by relay Q^c.

The operation of the track relays is as follows: When the section to the right of point C is occupied, track relay Q^c is, of course, de-energized. Current of one relative polarity, which I will term "reverse" relative polarity, is then supplied to the rails of section B—C from secondary 7 of transformer T^c, so that track relay Q^b is energized in the reverse direction. Current of the opposite or normal relative polarity is, therefore, supplied to the rails of section A—B from secondary 7 of transformer T^b, so that relay Q^a is energized in the normal 30 direction. Current of normal relative polarity is consequently supplied to the rails of the section to the left of point A by secondary 7 of transformer T^a.

It will be seen from the foregoing that, 35 if desired, trackway signals may be controlled by the track relays Q. I have shown such a signal at point B, but have omitted the trackway signals from points A and C to simplify the drawing. The signal at point B comprises three lamps 48, 49 and 50, adapted when lighted to indicate "proceed", "caution" and "stop", respectively. These lamps are supplied with current from a battery 51 and the lamps are controlled by 40 a contact 11 on relay Q^b in such manner that the proceed lamp 48 will be lighted when relay Q^b is energized in normal direction, the caution lamp 49 is lighted when relay Q^b is energized in the reverse direction, and the 45 stop lamp 50 will be lighted when relay Q^b is de-energized.

Located in the section to the left of point A is a train W provided with apparatus selectively responsive to the frequencies of 55 the currents in the track rails. This apparatus comprises three pairs of coils F⁷, F^a and F^b, located in front of the train and in inductive relation to the rails 1 and 2, so that alternating train governing currents in 60 the track rails induce alternating currents in the train carried coils. The coils F⁷ supply current to electro-responsive apparatus D⁷, the coils F^a supply current to electro-responsive apparatus D^a, and the coils F^b supply 65 current to electro-responsive apparatus D^b.

Referring now to Fig. 2, the apparatus D comprises a vibrating relay J having a U-shaped core 29 and an armature 31. The core 29 is provided with operating coils 30 which are connected with the receiving coils 70 F. The armature 31 is mounted on a spring 34 and carries a weight 35, and the armature is polarized by suitable means, such for example, as a coil 32 supplied with current by a battery 33. The armature 31 is mechanically tuned by the spring support 34 and the weight 35 to resonance at the frequency of one of the train governing currents supplied to the track rails. Armature 31 controls a contact 37 which is open when the armature 80 occupies its intermediate or de-energized position, but is closed when the armature is swung in either direction from such position. The two fixed members 37^a and 37^b of this contact are connected respectively with the two terminals of a battery 36, the middle point of which battery is connected through a wire 38 with one terminal of the primary 39 of a transformer K. The spring support 34 is connected with the other terminal of primary 39, through wires 41 and 41^a and a condenser 40. The circuit including the primary of transformer K is tuned by the condenser 40 to resonance at the frequency at which the armature 31 is mechanically 85 tuned. It follows that when coils F are energized with alternating current of the frequency for which the armature 31 is tuned, this armature will vibrate and so will cause 90 pulsating current of such frequency to flow in the primary 39 of transformer K. Owing to the electrical tuning of the circuit for this primary, forced vibrations of armature 31 at any other frequency will cause only a 95 comparatively small amount of pulsating current to flow in the transformer primary, which amount is insufficient to actuate the apparatus supplied by transformer K, and hereinafter described. That is, the capacity of battery 36 may be such that when the contact 37 is operated at any frequency other than that to which the primary circuit of transformer K is tuned, the current output 100 of the secondary of this transformer will be less than the value required to operate the apparatus associated with such secondary. The secondary 42 of transformer K supplies 105 current to a rectifier 43, which in turn delivers uni-directional current to a relay H. It will be observed that if the armature 31 sticks in such position that either contact 37^a or 37^b is closed, continuous current will 110 flow in the primary 39 of transformer K and this current will, of course, not induce current in the transformer secondary 42.

In the form of apparatus shown in Fig. 2, the condenser 40 is in series with primary 39 and contact 37, so that this primary circuit is tuned to series resonance at the frequency at which the apparatus is to respond.

- If desired, this primary circuit may be tuned for current resonance in the manner shown in Fig. 3, wherein the condenser 40 is connected in multiple with transformer 5 primary 39. In this form of the apparatus the local circuit including primary 39 and condenser 40 is tuned to resonance at the frequency to which the apparatus is to respond.
- Again referring to Fig. 1, and considering the apparatus D⁷, this apparatus is mechanically and electrically tuned to resonance at the frequency supplied by the secondaries 7 of transformers T. The apparatus D⁶ is mechanically and electrically tuned to the frequency of the current delivered by generators G⁶, and the apparatus D⁵ is mechanically and electrically tuned to the frequency delivered to generators G⁵.
- It follows that relays H⁷, H⁶ and H⁵ will respond selectively to the currents delivered by secondary 7, generator G⁶ and generator G⁵, respectively.
- Located on the train W is a signal S, comprising three electric lamps G, Y and R, arranged when lighted to indicate "proceed", "caution", and "stop", respectively. The proceed lamp G is provided with a circuit which passes from battery 13, through wire 14, lamp G, wire 15, front contact 16 of relay H⁵, wires 17 and 17^a, front contact 18 of relay H⁷, and wire 19 to battery 13. It follows that this lamp is lighted only when relays H⁵ and H⁷ are both energized. The caution lamp Y, is provided with a circuit which passes from battery 13, through wire 14, lamp Y, wire 20, front contact 21 of relay H⁶, wires 22 and 17^a, front contact 18 of relay H⁷, and wire 19 to battery 13. This lamp is lighted, therefore, only when relays H⁶ and H⁷ are both energized. The stop lamp R is provided with a circuit which passes from battery 13, through wire 14, lamp R, wires 23 and 24, back contact 25 of relay H⁵, wire 26, back contact 27 of relay H⁶, and wires 19^a and 19 to battery 13. In so far as this circuit is concerned, lamp R will be lighted only when relays H⁵ and H⁶ are both de-energized. This circuit is provided with a branch, however, which passes from wire 23, through wire 28 and back contact 18 of relay H⁷ to wire 19; it follows, therefore, that lamp R will be lighted when relay H⁷ is de-energized.
- The operation of the train-carried apparatus is as follows:
- As shown in the drawing, the section to the right of point C is occupied by a train W', so that track relay Q^C is de-energized, and track relays Q^B and Q^A are both energized. The train W is, consequently, receiving currents of frequencies 7 and 5, so that relays H⁷ and H⁵ are energized, with the result that the proceed indication lamp G is lighted. This condition will continue until the train W reaches point B, whereupon the train-carried apparatus will receive currents of frequencies 7 and 6. Relays H⁷ and H⁶ will then be energized so that the caution lamp Y will be lighted and the proceed lamp G will become extinguished. When the train passes point X in section B-C the supply of current of frequency 6 to the train coils will be discontinued, so that relays H⁶ and H⁵ will both be de-energized and relay H⁷ will be energized. This will cause the caution lamp Y to be extinguished and the stop lamp R to become lighted. As the train W passes point C, and enters the section occupied by train W', the supply of all train governing current will be discontinued, so that relays H⁵, H⁶ and H⁷ will all be de-energized, with the result that the stop lamp R will continue to be lighted.
- Assuming that train W' is between points X and C in section B-C, and that train W is between points B and X in the same section, it will be observed that relay H⁶ may be energized from generator G⁶ at point C. Relays H⁷ and H⁵ will both be de-energized, however, because currents of frequencies 5 and 7 are shunted by the wheels and axles of train W', so that lamps G and Y will be extinguished and the stop lamp R will be lighted.
- The apparatus on the train W is so connected that the failure of frequency 7 or the failure of either of the other two frequencies at the time that they are supposed to be active will give a stop indication. That is to say, in the event of failure of frequency 7 relay H⁷ will become deenergized, thereby opening at its front contact 18 the circuits for the proceed and caution lamps G and Y and closing at its back contact 18 the circuit for stop lamp R. Normally only one of the other two frequencies 5 and 6 is supplied to the train at one time. The relay corresponding to the other of these frequencies is, therefore, de-energized. If the one that is supposed to be energized fails for any reason, such as failure of the current supply, this relay is de-energized so that both relays H⁵ and H⁶ are de-energized, thereby opening the circuits for the proceed and caution lamps G and Y and closing the circuit for the stop lamp R.
- Although I have herein shown and described only certain forms of apparatus embodying my invention, it is understood that various changes and modifications may be made therein within the scope of the appended claims without departing from the spirit and scope of my invention.
- Having thus described my invention, what I claim is:
1. Railway traffic controlling apparatus comprising a section of track, sources of alternating train governing current of three different frequencies for said section, means

- controlled by traffic conditions in advance for connecting the first and second sources with the rails of said section under one condition and for connecting the first and third 5 of said sources with the rails of said section under another condition, and train-carried apparatus selectively responsive to the frequencies of the currents supplied to the rails of said section.
- 10 2. Railway traffic controlling apparatus comprising a section of track, sources of alternating train governing current of three different frequencies for said section, means controlled by traffic conditions in advance 15 for connecting the first and second sources with the rails at the exit end of said section under one condition and for connecting the first source with the rails at the exit end and the third source with the rails at an intermediate 20 point in the section under another condition, and train-carried apparatus selectively responsive to the frequencies of the currents supplied to the rails of said section.
- 25 3. Railway traffic controlling apparatus comprising a section of track, sources of alternating train governing current of three different frequencies for said section, the first of which is constantly connected with the rails at the exit end of the section, means 30 controlled by traffic conditions in advance for at times connecting the second source with the rails at the exit end of the section and for at other times connecting the third source with the rails at an intermediate point in the 35 section, and train-carried apparatus selectively responsive to the frequencies of the currents supplied to the rails of said section.
- 40 4. Railway traffic controlling apparatus comprising a section of track, sources of alternating train governing current of three different frequencies for said section, the first of which is constantly connected with the rails at the exit end of the section, means controlled by traffic conditions in advance for 45 also connecting the second or the third source with the rails of said section, and train carried apparatus selectively responsive to the frequencies of the currents supplied to the rails of said section.
- 50 5. Railway traffic controlling apparatus comprising a track divided into sections, sources of alternating train governing current of three different frequencies for each section the first of which sources is constantly connected with the rails at the exit end of the associated section, a track relay for each section responsive to the frequency of said first source but not to the frequencies of the other two sources, means for each section for 55 connecting the second source with the rails at the exit end when the relay for the section next in advance is energized and for connecting the third source with the rails at an intermediate point in the section when the relay for the next section in advance is de-en-

ergized, and train carried apparatus selectively responsive to the frequencies of the currents in the rails.

6. Railway traffic controlling apparatus comprising a track divided into sections, sources of alternating train governing current of three different frequencies for each section the first of which sources is constantly connected with the rails at the exit end of the associated section, a track relay for each section responsive to the frequency of said first source but not to the frequencies of the other two sources, means for each section for connecting the second source or the third source with the rails of the section according as the track relay for the section next in advance is energized or de-energized, and train carried apparatus selectively responsive to the frequencies of the currents in the rails. 75 80 85

7. Railway traffic controlling apparatus comprising a track divided into sections, means for constantly supplying train governing current of a first frequency to each section, a track relay for each section selectively responsive to current of said first frequency, means for each section for supplying thereto a train governing current of a second or a third frequency according as the track relay for the section next in advance is energized or de-energized, and train-carried apparatus selectively responsive to the frequencies of the currents supplied to said sections. 90 95

8. Railway traffic controlling apparatus comprising a track divided into sections, means for constantly supplying alternating train governing current of one frequency to the exit end of each section, a track relay for each section selectively responsive to current of said first frequency, means for each section for supplying train governing current of a second frequency to the exit end of the section when the track relay for the section next in advance is energized and for supplying train governing current of a third frequency to an intermediate point in the section when the track relay for the section next in advance is de-energized, and train-carried apparatus selectively responsive to the frequencies of the currents supplied to the sections. 100 105 110 115

9. Railway traffic controlling apparatus comprising a track divided into sections, sources of alternating train governing current of three different frequencies for each section, a track relay for each section selectively responsive to current of the first of said frequencies and also responsive to the relative polarity of the current of said first frequency in the track rails, means for each section for connecting the first source with the rails of the section in one direction or the other according as the track relay for the section next in advance is energized or 120 125 130

de-energized, means for each section for also connecting the second source or the third source with the rails of the section according as the track relay for the section next in advance is energized or de-energized, and train-carried apparatus selectively responsive to the frequencies of the currents supplied to the rails.

10. Railway traffic controlling apparatus comprising a track divided into sections, sources of alternating train governing current of three different frequencies for each section, a track relay for each section selectively responsive to current of the first source and also responsive to the relative polarity of such current in the track rails, means for each section for connecting the first source with the rails at the exit end of the section in one direction or the other according as the track relay for the section next in advance is energized or de-energized, means for each section for connecting the second source with the rails at the exit end of the section when the relay for the section next in advance is energized and for connecting the third source with the rails at an intermediate point in the section when the relay for the section next in advance is de-energized, and train-carried apparatus selectively responsive to the frequencies of the currents supplied to the rails.

11. Railway traffic controlling apparatus comprising a section of railway track, means for supplying said section with train governing currents of a first and a second frequency under one condition of traffic in advance and with train governing currents of said first and a third frequency under a different condition of traffic in advance, first, second and third train carried relays responsive respectively to said three trackway currents, and means controlled by said relays for giving a proceed indication when the first and second relays are energized and a caution indication when said first and third relays are energized and a stop indication when said first relay is de-energized or said second and third relays are both de-energized.

12. Railway traffic controlling apparatus comprising a section of railway track, means for supplying train governing currents of a first and a second frequency to the rails at the exit end of said section under one condition of traffic in advance and for supplying train governing current of the first frequency to the rails at the exit end of the section and train governing current of a third frequency to the rails at an intermediate point in the section under a different condition of traffic in advance of the section, first, second and third train carried relays responsive respectively to said three trackway currents, and means controlled by said relays for giving a proceed indication

when the first and second relays are energized and a caution indication when said first and third relays are energized and a stop indication when said first relay is de-energized or said second and third relays are both de-energized.

13. Railway traffic controlling apparatus comprising a section of track, sources of alternating train governing current of three different frequencies for said section, means controlled by traffic conditions in advance for connecting the first and second sources with the rails at the exit end of said section under one condition and for connecting the first source with the rails at the exit end and the third source with the rails at an intermediate point in the section under another condition, first, second and third train carried relays responsive respectively to said three trackway currents, and means controlled by said relays for giving a proceed indication when the first and second relays are energized and a caution indication when said first and third relays are energized and a stop indication when said first relay is de-energized or said second and third relays are both de-energized.

14. Railway traffic controlling apparatus comprising a section of track, sources of alternating train governing current of three different frequencies for said section, the first of which is constantly connected with the rails of the exit end of the section, means controlled by traffic conditions in advance for at times connecting the second source with the rails at the exit end of the section and for at other times connecting the third source with the rails at an intermediate point in the section, first, second and third train carried relays responsive respectively to said three trackway currents, and means controlled by said relays for giving a proceed indication when the first and second relays are energized and a caution indication when said first and third relays are energized and a stop indication when said first relay is de-energized or said second and third relays are both de-energized.

15. Railway traffic controlling apparatus comprising a section of track, sources of alternating train governing current of three different frequencies for said section, the first of which is constantly connected with the rails at the exit end of the section, means controlled by traffic conditions in advance for also connecting the second or the third source with the rails of said section, first, second and third train carried relays responsive respectively to said three trackway currents, and means controlled by said relays for giving a proceed indication when the first and second relays are energized and a caution indication when said first and third relays are energized and a stop indication when said first relay is de-energized or said

second and third relays are both de-energized.

16. Railway traffic controlling apparatus comprising a track divided into sections, 5 sources of alternating train governing current of three different frequencies for each section the first of which sources is constantly connected with the rails at the exit end of the associated section, a track relay 10 for each section responsive to the frequency of said first source but not to the frequencies of the other two sources, means for each section for connecting the second source with the rails at the exit end when the relay for 15 the section next in advance is energized and for connecting the third source with the rails at an intermediate point in the section when the relay for the next section in advance is de-energized, first, second and third 20 train carried relays responsive respectively to said three trackway currents, and means controlled by said relays for giving a proceed indication when the first and second relays are energized and a caution indication 25 when said first and third relays are energized and a stop indication when said first relay is de-energized or said second and third relays are both de-energized.
17. Railway traffic controlling apparatus 30 comprising a track divided into sections, sources of alternating train governing current of three different frequencies for each section the first of which sources is constantly connected with the rails at the exit 35 end of the associated section, a track relay for each section responsive to the frequency of said first source but not to the frequencies

of the other two sources, means for each section for connecting the second source or the third source with the rails of the section according as the track relay for the section next in advance is energized or de-energized, first, second and third train carried relays responsive respectively to said three trackway currents, and means controlled by said 40 relays for giving a proceed indication when the first and second relays are energized and a caution indication when said first and third relays are energized and a stop indication when said first relay is de-energized or said 45 second and third relays are both de-energized.

18. Railway traffic controlling apparatus comprising a section of railway track, 55 means for supplying said section with train governing currents of a first and a second frequency under one condition of traffic in advance and with train governing currents of said first and a third frequency under a different condition of traffic in advance, first, 60 second and third train carried relays responsive to said first, second and third trackway currents, respectively, a proceed indication circuit controlled by front contacts of said first and second relays, a caution indication circuit controlled by front contacts of said first and third relays, a stop indication circuit controlled by back contacts of 65 said second and third relays, and a branch for said stop indication circuit around said 70 back contacts and including a back contact of said first relay.

In testimony whereof I affix my signature.
LARS O. GRONDAHL.
